(57) **CLAIM**

The ornamental design for a scooter, as shown and described.

DESCRIPTION

FIG. 1 is a front and top perspective view of a scooter, showing our new design;

FIG. 2 is a rear and bottom perspective view thereof;

FIG. 3 is a front elevation view thereof;

FIG. 4 is a rear elevation view thereof;

FIG. 5 is an enlarged left side elevation view thereof;

FIG. 6 is an enlarged right side elevation view thereof;

FIG. 7 is an enlarged top plan view thereof;

FIG. 8 is an enlarged bottom plan view thereof;

FIG. 9 is an enlarged perspective view of detail "9" identified in FIG. 1;

FIG. 10 is an enlarged perspective view of detail "10" identified in FIG. 1;

FIG. 11 is an enlarged perspective view of detail "11" identified in FIG. 1;

FIG. 12 is an enlarged perspective view of detail "12" identified in FIG. 1;

FIG. 13 is an enlarged perspective view of detail "13" identified in FIG. 2; and,

FIG. 14 is an enlarged perspective view of detail "14" identified in FIG. 2.

The dashed lines in the figures illustrate portions of the scooter that form no part of the claimed design. The dash dot dash lines in FIGS. 1, 2, 9, 10, 11, 12, 13 and 14 are for the purpose of illustrating the enlarged views indicators and form no part of the claimed design.
